UNITED STATES PATENT OFFICE.

ROBERT EDWARD ARGY, OF NIAGARA FALLS, NEW YORK.

APPARATUS FOR MAKING PAPER.

Application filed July 9, 1928. Serial No. 291,273.

This invention relates to a method of and to apparatus for making paper.

One object of the invention is to provide a novel and improved method of making paper in which the web of paper is subject to a pre-heating operation preliminary to its passage through the last set of wet presser rolls, and in which the pre-heating treatment is effected in a novel and economical manner.

A further object of the invention is to provide novel apparatus for the manufacture of paper adapted to permit pre-heating the paper web before the web passes through the last set of wet presser rolls, and which is of a construction such as to permit existing paper machines to be modified to produce the improved apparatus in a simple, economical manner involving minimum alterations in the construction and operation of such existing paper machines.

With these objects in view and such others as may hereinafter appear, the invention consists in the improved method of making paper and in the apparatus herein-after described and particularly defined in the claims at the end of this specification.

In the drawing, a sufficient portion of the improved paper machine has been illustrated to enable the features of the present invention to be understood, wherein Figure 1 is a diagrammatic view illustrating the dry end of such a machine; and Fig. 2 is a plan view illustrating the drive for the baby drier.

While the idea of subjecting a paper web to pre-heating during the passage of the web through the paper machine prior to the time that it has completed its passage through the wet pressing apparatus, is not broadly new, nevertheless the arrangement of apparatus heretofore proposed for performing the pre-heating operation has in some instances involved the reconstruction and relocation of material parts of the paper machine.

An arrangement heretofore proposed comprises that forming the subject matter of the patent to John C. Corcoran No. 1,690,402 granted November 6, 1928, to which reference may be made and which in its preferred form includes a nest of three steam-heated cylinders and mechanism for driving the same. Such pre-heating cylinders were preferably interposed between the second and third pairs of press rolls of the wet pressing apparatus of the paper ma-

chine, and the web of paper was passed around the individual heating cylinders to be pre-heated before being passed through the last wet presses. While such apparatus has performed its function satisfactorily, and while as a result of such pre-heating operation additional water was extracted by the last wet press roll with resulting economies in the steam consumed in final drying and in rendering possible an increased production in the paper machine, nevertheless the installation of the nest of steam pre-heating drums usually necessitated relocation of the last pair of wet press rolls and other changes in the existing paper machine, all of which involve considerable expense and inconvenience. In some paper mills the lack of room has presented a serious obstacle to the incorporation of the Corcoran pre-heating drums into the paper machine.

The present invention contemplates a paper machine in which novel provision is made for pre-heating the web of paper before it passes onto the final driers and prior to the time that it has completed its passage through the wet pressing apparatus to the end that a maximum amount of water may be mechanically extracted or pressed from the web and economy secured in the final drying operation. In accordance with the present invention existing paper machines may be conveniently and with minimum alteration adapted to the present arrangement and in many instances the present invention enables an existing paper machine to be equipped with means for pre-heating the paper web for the purpose described where otherwise such a result would be impossible because of the lack of room and other difficulties attending the alteration of the paper machine in the mill. In addition the present paper machine enables a superior finish to be imparted to the paper and improved folding qualities to be obtained.

In the drawing illustrating the preferred form of the invention, a sufficient portion of a paper machine has been therein illustrated to enable the invention to be understood, and in which 10 represents the web of paper in the condition in which it exists after having been formed in the usual way and is being conducted to the first presses of the wet pressing apparatus. The paper web during its passage through the press rolls 12, 14 comprising the first presses is supported

upon the usual form of felt 15, and a portion of the water is extracted by the press rolls 12, 14. Thereafter the web is conducted from the first presses toward the second 5 presses down to a point adjacent one of the felt carrying rolls 16 and thence around the usual paper guide roll 17 from which it is conducted around the baby drier 20 and thence through a second set of wet press 10 rolls 22, 24, and around the usual guide roll 26 and over a guide roll 28 and thence around the successive steam-heated drums 30 of the usual set of drying cylinders which perform the final drying operation.

15 The baby drier 20 is arranged to be driven in the direction of the arrow 31, reverse to its normal direction of rotation and at a speed synchronized with respect to the speed of the second set of wet press rolls 22, 24, so 20 as to maintain the web in an even smooth condition during its passage over the baby drier and through the wet press rolls. As shown in Fig. 1, the normal direction of rotation of the baby drier 20 is indicated 25 by the arrow 32. As herein shown the baby drier is arranged to be driven through a sprocket chain 33 running around a pair of sprockets 36, 37 upon the baby drier and the felt carrying roll respectively, so that the 30 baby drier is driven in timed relation to the felt carrying roll and is arranged to preserve the linear speed of the paper to prevent the formation of irregularities in the paper.

From the description thus far it will be 35 observed that the only alteration required in adapting an existing paper machine of the type employing a baby drier to the present invention is that the direction of rotation of the baby drier be reversed and suitable provision made for driving the baby drier in 40 such reverse direction and at a speed synchronized with the speed of the last wet press rolls. These alterations may be made at a relatively small expense without seriously interfering with the continuance of 45 the paper machine in operation.

In addition to the simplicity with which an ordinary paper machine may be modified to embody the present invention, it has been 50 observed that the condition of the paper web before passing onto the final set of driers is much drier than with the ordinary machine, and as a result economies in the steam consumption in the final driers may be secured 55 and a substantial increase in production for a given drier capacity may be obtained. As an example of the economies which may be obtained, in one paper machine prior to the embodiment of the present invention, the 60 steam pressure on the final driers averaged about 40 pounds, and after embodying the present invention satisfactory drying was obtained utilizing only 30 pounds of steam in the driers. It was found possible to increase 65 the speed of the machine from 375 feet per

minute up to 425 feet per minute before the steam pressure was brought back to 40 pounds, thereby increasing the production of the machine a little over 13%. The machine made 2046 pounds of paper per hour before 70 the modification, and made 2321 pounds of paper per hour after the modification was made. For example, a paper mill producing 75 40 tons of paper at the present time may, by modifying its paper machines in accordance with the present invention, produce an additional four tons of paper per day, amounting to a saving of approximately eighty dollars (\$80.00) per day.

In addition to the economies resulting directly from the increased quantity of water mechanically extracted by the wet pressing apparatus, it has been found that the heating of the paper web before it enters the last wet press has somewhat the effect of a smoothing press. The paper is compressed somewhat in a warm state, thus increasing its strength and folding qualities, and improving the feel and surface of the paper.

It is to be understood that while it is 90 preferred to heat the pre-heating roll with steam, nevertheless other means of heating may be used if desired.

While the preferred embodiment of the invention has been illustrated and described, 95 it will be understood that the invention may be embodied in other forms within the scope of the following claims.

Having thus described the invention, what is claimed is:—

1. In a paper machine, the combination with the last set of wet press rolls, of a baby drier, means for guiding the paper web around the baby drier to pre-heat the same and then through said press rolls, and means 105 for driving the baby drier in synchronism with said press rolls.

2. In a paper machine, the combination with the last set of wet press rolls, of a baby drier, means for guiding the paper web 110 under said press rolls and up around said baby drier to pre-heat the web and thence through the press rolls, and means for rotating the baby drier in a direction reverse to its usual direction of rotation and in synchronism with said press rolls.

3. In a paper machine, the combination with a set of drying rolls mounted in staggered relation, of the last pair of wet press rolls, means for guiding the paper web 120 around the endmost drying roll to pre-heat the same, and thence through said wet press rolls, and thence around the second drying roll, and means for driving the endmost drying roll in synchronism with said wet press 125 rolls.

In testimony whereof I have signed my name to this specification.

ROBERT EDWARD ARGY.
